UNITED STATES PATENT OFFICE.

GEORGE H. SPAULDING, OF CHICAGO, ILLINOIS.

MOWING-MACHINE.

SPECIFICATION forming part of Letters Patent No. 359,023, dated September 4, 1888.

Application filed February 14, 1887. Serial No. 227,642. (No model.)

To all whom it may concern:

Be it known that I, GEORGE H. SPAULDING, of Chicago, in the county of Cook and State of Illinois, have invented new and useful Improvements in Mowing-Machines, of which the following is a specification, reference being had to the accompanying drawings, forming a part thereof.

My invention has reference to that ordinary type of mowing-machines in which the cutting mechanism, united to a wheel-frame by jointed connections, is also connected with a hand-lever, by which it is lifted at the inner or heel end.

The object of my invention is to apply a spring in such manner that it will assist in sustaining the weight of the finger-bar for the double purpose of carrying the cutter over the ground with an easy yielding action, and of relieving the operator of a portion of the weight when lifting the bar out of action.

My invention consists in the combination of the spring with devices peculiarly constructed and arranged to operate in connection therewith, as hereinafter described in detail, and particularly pointed out in the claims.

As the machine may be in all other respects of ordinary construction, I have represented in the drawings only those parts which are immediately associated with my improvement.

Figure 1 is a front elevation of one side of a mower-frame with my improvements applied thereto. Fig. 2 is a side elevation of the same, a portion of the main wheel being broken away to expose the other part to view. Fig. 3 is a side view of the lifting-lever and part attached thereto. Fig. 4 is a horizontal section through the axis of the hand-lever. Fig. 5 is an end view of the spring.

Referring to the drawings, A represents a portion of the main frame; B, the draft pole or tongue bolted firmly thereto; C, one of the ground-wheels mounted on a journal extending from the side of the frame; D, the inner or heel end of the finger-bar; F, the arm for sustaining the same jointed at one end to the bar and at the opposite end to the frame; G, an angular hand-lever, commonly known as the "lifting-lever," mounted on a fixed stud, I, projecting from the frame and connected by

a chain, H, to the arm F to control the elevation of the finger-bar and lift it over obstructions or out of action, as required. In their general construction and arrangement the foregoing parts are similar to those now in general use; but the hand-lever and its connections possess certain features of novelty, which will now be explained.

The stud I, on which the lever is mounted, is provided with a threaded neck or shoulder, a, which is passed through a vertical plate or web, b, on the side of the main frame and secured by a nut, c, on the inner end, its rotation being prevented by a stud, d, projecting from its side and seated in a notch in the frame, as shown in Fig. 4. The hand-lever is provided with a tubular journal or sleeve, d', through which the pivot passes, and is also provided near one end with an annular flange, e, recessed on one side. On the outer end of the stud or pivot I there is mounted a corresponding flange or cup, f, fixed against rotation by a pin or cotter, g, passing through its hub and through the stud I. The hub of this flange is provided, as shown, with a series of notches to receive the cotter, so that it may be rotated and fixed in different positions for the purpose of regulating the tension of the spring, as hereinafter explained. A strong spiral spring, h, encircles the sleeve of the hand-lever and is formed with two outwardly-turned ends, one of which is seated in the flange e of the lever, while the other is seated in a notch in the stationary flange f. The spring, being thus applied, urges the lever constantly backward, and, its tension being properly regulated, it assists in carrying the weight of the finger-bar, which is thus enabled to ride easily over inequalities in the surface of the ground and over the obstructions which may be encountered. Owing to the tendency of the spring to turn the lever and lift the finger-bar, the operator is enabled to carry the bar over obstructions or to lift it out of action with much less labor than is ordinarily required.

It is sometimes desirable to render the spring inoperative by locking the lever, so that the spring cannot move to lift the finger-bar. For this purpose I pivot a dog or pawl, i, to the lower end of the lifting-lever and provide the

main frame with a flange, *k*, with which the dog may engage when the lever is in different positions. A rod, *l*, is extended from the dog to a thumb-latch, *m*, pivoted to the upper end 5 of the hand-lever as a means of lifting the dog, and a spiral spring, *n*, is applied around the rod for the purpose of urging the dog downward. When the hand-lever is moved to the rear, it lifts the finger-bar, and if the motion be 10 continued a sufficient distance the dog *i*, moving to the front, will finally pass the forward end of the flange *k* and, dropping in front of the same, will lock the lever and hold the finger-bar in its elevated position. When the lever 15 is thrown forward to an extreme position, the dog will engage behind the flange *k* and thus lock the lever forward, so that the spring is for the time being inoperative, the flexible chain or suspension device allowing the cutter 20 devices to rise and fall independently of the lever, and thus follow the surface of the ground. In ordinary positions of the lever the dog rides on top of the flange *k* and is inoperative.

In order that the dog may be locked permanently out of action when required, I propose to provide any suitable device for the purpose. A simple device is that represented in Fig. 2, in which it will be seen that the thumb latch *m* and the hand-lever are provided 25 with holes *p* to receive a pin, *g*, suspended from the hand-lever. When the thumb-latch is turned upward, so that the two holes register, the dog is lifted clear of the flange *k*. The pin being inserted in the hole maintains the dog 30 in this position.

While I have described the recessed flanges or cups to inclose and protect the spring, and while I prefer to employ them, it is to be understood that they are not a necessary feature 35 of the machine.

I am aware that springs have been variously applied to and in carrying and lifting the cut-

ting mechanism of mowing-machines, and this I do not broadly claim, my invention residing in the improved manner of constructing and arranging the several parts to that end, as herein described and specifically claimed. 45

Having thus described my invention, what I claim is—

1. In a mowing-machine, the main frame, 50 the stud *I*, provided with the head at its outer end and fixed at its inner end immovably to the frame, in combination with the cutter-lifting lever provided with the notched flange *e*, the notched collar or cuff *f*, mounted on and adjustable around the stud, as described, and the spring encircling the stud and fixed at one end to the flange *e* and at the other to the collar *f*. 55

2. In combination with the main frame and 60 the cutting mechanism jointed thereto to rise and fall, the stud *I*, fixed to the main frame, the lifting lever mounted on the stud and connected with the cutting mechanism, the collar *f*, provided with the notched hub and seated on 65 the stud, the pin or cotter *g*, holding the collar adjustably in place on the stud, and the helical spring having one end connected to said adjustable collar and the other connected to the lever. 70

3. In a mowing-machine, the cutter-lifting lever united to the cutter by the chain or similar connection, in combination with the spring acting on the lever and tending constantly to raise the cutter, the locking-dog on the lever, and the stationary unbroken flange *k*, whereon the dog rides, adapted to engage and hold the dog only when the lever is thrown to an extreme position forward or backward. 75

GEORGE H. SPAULDING.
